UNITED STATES PATENT OFFICE.

FREDERICK G. HAAGE, OF CLIFTON, NEW JERSEY.

SNAP.

Application filed May 15, 1924. Serial No. 713,535.

To all whom it may concern:

Be it known that I, FREDERICK G. HAAGE, a citizen of the United States, and a resident of Clifton, in the county of Passaic and 5 State of New Jersey, have invented a new and Improved Snap, of which the following is a full, clear, and exact description.

This invention relates to snaps and particularly to an improved snap especially 10 adapted for wrist watch bands whereby the band may be quickly and easily adjusted.

An object of the invention is to provide 15 a snap for bands or belt members wherein the material of the band or belt is not pierced.

Another object of the invention is to provide 20 a snap for connecting the free ends of a belt or strap together, the arrangement being such that part of the snap is carried by each of the free ends.

A further object, more specifically, is to provide 25 a snap which may be used for the bands of wrist watches and which permits of ornamentation arranged in such a manner as to show the band therethrough.

In the accompanying drawing—

Figure 1 is a perspective view of a wrist 30 watch and band, together with the snap embodying the invention.

Figure 2 is a fragmentary perspective view of a band showing the snap embodying the invention applied thereto with the parts separated.

Figure 3 is an enlarged perspective view 35 of a fixed part or half of the snap shown in Figure 2.

Figure 4 is a perspective view of the movable part or half of the snap shown in Figure 2.

Figure 5 is a sectional view through Figure 1, approximately on line 5—5, the same being on a slightly enlarged scale.

Figure 6 is a view similar to Figure 5 but showing the parts partially disengaged.

Figure 7 is a plan view of a slightly modified form of snap together with a short section of band.

Figure 8 is a perspective view similar to Figure 4 but showing the modified structure 50 illustrated in Figure 7.

Figure 9 is a perspective view of part of the snap shown in Figure 7, the same co-acting with the part shown in Figure 8.

Figure 10 is a sectional view through Figure 7, approximately on line 10—10, the same being on an enlarged scale.

Referring to the accompanying drawing by numerals, 1 indicates a wrist watch of any desired kind provided with a strap or band 2 which may be of cloth, leather or other desired material to which the snap or fastening member 3 is secured, said snap or fastening member acting to connect the free ends of the band together whereby the watch 1 is held in place on the wrist when 60 in use. It will be understood that the snap or fastener 3 could be used for other purposes without departing from the spirit of the invention, though it lends itself particularly to wrist watch bands and similar devices where an ornamental fastening is desired.

The snap 3 is formed into what be termed a fixed or base part 4 and a movable or adjustable part 5. The base part 4 is provided with an eye 6 through which the end of the strap 2 is looped as shown in Figure 2 and the folded or looped section 7 secured in place by stitching or in any desired manner. In forming the eye 6, a bar 8 will be formed, over which the end 7 is looped.

As shown in Figure 3, the base 4 at one edge is bent up for forming a resilient hook member 9 which is cut or divided at 10. Co-acting with the hook member 9 is a 75 resilient hook member 11 notched at 12. The notches 10 and 12 are to receive the aligning projections 13 and 14 of the adjustable part 5. This adjustable part is formed with slots or eyes 15 and 16 whereby a comparatively wide central bar 17 will be formed and co-acting edge bars 18 and 19 will be formed.

The adjustable part 5 is moved along the strap or band 2 until the desired adjustment is secured and then the same is forced into the base 4 until it moves to the position shown in Figure 5. During the operation of forcing the part 5 into position, the same is first placed as shown in Figure 6 with the lug 13 in notch 10. The parts are then pivoted or swung together until the bar 19 snaps into the hook 11. It 90 will be noted that these hook members are sufficiently resilient to allow ready movement in and out but to resist said movement appreciably in order to prevent any accidental disengagement. It will also be noted that the lugs 13 and 14 will prevent any independent longitudinal movement of the part 5 while engaging base 4.

In forming the base 4 in this manner, there is ample space for providing orna- 100 105 110

mentation 20 and in forming this ornamentation, the base may be cut entirely through so as to expose the band 2 therebeneath as shown in Figures 1 and 7. This 5 ornamentation may be in the nature of a person's initials or some fanciful matter.

In Figures 7 to 10 inclusive, will be seen a modified construction, which in principle, is the same as the preferred structure 10 but re-arranged so that the respective hooks 9' and 11' will be at the ends of the body of base 4'. Each of these resilient hooks is provided with a notch 21 for receiving the lugs 22 and 23 of the part 5'.

15 What I claim is:

1. A snap for belts, bands and the like, comprising a base having a bar for receiving a strap, a pair of spaced resilient hook members, each of said hook members having 20 a notch, and a co-acting movable part formed with openings through which said strap may be threaded, said part being of

a width to fit snugly within said resilient hooks, said part also being formed with projections adapted to project into said 25 notches whereby independent longitudinal movement cannot take place.

2. A fastener for connecting the free ends of a band together, comprising a base formed with means for receiving one end of the band and with oppositely facing resilient hook members, an adjustable member adapted to be slidably mounted on said band, said adjustable member having a pair of spaced longitudinal slots through which 30 said band is threaded, and a projection, said base being formed with a notch for receiving said projection, said resilient hook members being spaced apart sufficiently to permit said adjustable member to snugly fit therebetween when said projection is fitting into said notch whereby the parts are resiliently held interlocked.

FREDERICK G. HAAGE.
